HYDROMASSAGE BATHTUB

Roy A. Jacuzzi, Moraga, and Peter L. Kosta, Lafayette, Calif., assignors to Jacuzzi Research, Inc.

Filed Jan. 26, 1972, Ser. No. 221,129

Term of patent 14 years

Int. Cl. D23—02

U.S. Cl. D83—1 C

FIG. 1 is a plan view of a hydromassage bathtub showing our new design;

FIG. 2 is a cross sectional view taken on line 2—2 of FIG. 1; and

FIG. 3 is a cross sectional view taken on line 3—3 of FIG. 1.

We claim:

The ornamental design for a hydromassage bathtub, as illustrated.
